ROLLING SUPPORT FOR GARMENT HANGERS

Daniel T. Hallahan, New York, N.Y., assignor to Sanjo Utility Mfg. Co. Inc., Brooklyn, N.Y.

Filed May 9, 1968, Ser. No. 11,864

Term of patent 14 years

Int. Cl. D6—07; D8—03

U.S. Cl. D80—8

FIGURE 1 is a front elevational view of a rolling support for garment hangers showing my new design;

FIGURE 2 is a side elevational view thereof;

FIGURE 3 is a side elevational view thereof, showing the side opposite that seen in FIGURE 2;

FIGURE 4 is a rear elevational view thereof;

FIGURE 5 is a top plan view thereof; and

FIGURE 6 is a bottom plan view thereof.

I claim:

The ornamental design for a rolling support for garment hangers, substantially as shown.
